RUNNING BOARD AND MEANS FOR ATTACHING THE SAME TO THE ROOF OF RAILWAY CARS

Charles S. Johnston, Chicago, Ill., assignor to Transportation Specialties Co., Chicago, Ill., a corporation of Illinois

Application February 16, 1951, Serial No. 211,346

4 Claims. (Cl. 108—5.4)

1

This invention relates to a running board and means for attaching the same to the roof of a railway car and has for its principal object the provision of an improved construction which will be highly efficient in use and economical in manufacture.

The standard and conventional railway car has a roof comprising a plurality of roof plates or sections arranged in substantially the same plane with abutting upwardly turned edge portions covered by seam caps. Such seam cap is riveted to the upturned edge portions by rivets at spaced intervals. It is an object of my invention to provide a running board and a mounting means therefor which in addition to being so constructed as to permit the mounting board and its attaching means to be installed as a single unit also utilizes certain of the seam cap rivets for firmly connecting the running board in position above the car roof along its longitudinal center line.

Another object of the invention is the provision of a running board of the class hereinafter described which by a simple operation can be installed upon the roof of a car with the minimum amount of expense and labor.

As railway cars are subjected to tremendous strain during transit and particularly in switching operations the several parts thereof are very often pushed out of alignment. This has frequently happened to the seam caps which are disposed over the upturned edges of the roof plates of the car and to which seam caps I contemplate connecting the running board through the medium of mounting plates. It is an object of the invention to construct these mounting plates in a manner such that the major portion of the plate will be spaced from the seam cap thereby to compensate for any irregularities in the formation or shape of such cap and to relieve any undue strain upon the rivets or other elements connecting the mounting plate to the seam cap due to conditions other than the normal weight of the running board and one or more persons thereon.

Another object of the invention is to provide a running board which will be substantially rigid and yet have a minimum of weight and one provided on its treading surface with anti-skid elements.

Another and equally important object of my invention is the provision of a running board for railway cars which is connected to the car roof in a manner such as to resist the usual strain subjected thereto by the operation of the car.

Other objects will appear hereinafter.

2

The invention consists in the novel combination and arrangement of parts to be hereinafter described and claimed.

The invention will be best understood by reference to the accompanying drawings showing the preferred form of construction, and in which:

Fig. 1 is a fragmentary perspective sectional detail view of a conventional railway car roof with which my invention may be associated;

Fig. 2 is a fragmentary sectional detail view taken substantially on line 2—2 of Fig. 5;

Fig. 3 is a fragmentary sectional detail view taken substantially on line 3—3 of Fig. 5;

Fig. 4 is a fragmentary sectional detail view taken substantially on line 4—4 of Fig. 2;

Fig. 5 is a fragmentary top plan view of the railway car illustrated in Fig. 1; and

Fig. 6 is a fragmentary sectional detail view taken substantially on line 6—6 of Fig. 3.

The several objects of my invention are preferably accomplished by the preferred form of construction shown in the accompanying drawings now to be referred to.

A conventional railway car is fragmentarily illustrated at 10. This railway car comprises a roof 11 made up of roof plates or sections 12 having upturned edge portions 13 arranged in abutting relation with respect to each other and covered by seam caps 14. Each seam cap 14 is rigidly and firmly connected to its respective upturned edge portions 13 by means of rivets 15 arranged at equal spaced intervals.

My improved running board and the means for mounting the same in position comprises a board section 16 of foraminous material to reduce the weight thereof to a minimum. On the top or treading surface of this board section are anti-skid elements 17. The longitudinal edges of the board section are bent downwardly and then inwardly to provide parallelly extending seating flanges 18.

The means for mounting the board section to the roof of the railway car comprises mounting plates 19 one arranged at each end of the section and one intermediate such ends. These plates are of elongated formation and prior to the installation of the running board are welded to the board section 16 so that such section and its mounting plates may be installed as a single unit.

The opposite end portions of these plates 19 are notched as at 20 to provide seats 21 for the seating flanges 18. In this manner the longitudinal edges of the running board are substantially reinforced by the mounting plates.

The running board provides longitudinally parallelly extending spaced apart ribs 22 intermediate the longitudinal edges thereof. The end mounting plates preferably abut the ends of these ribs as at 23 and are welded thereto. Where a mounting plate is utilized intermediate the ends of the running board such intermediate mounting plate (see Figs. 3 and 4) is provided with slots 24 into which these reinforcing ribs are seated.

The end portions of each of the plates 19 extend outwardly and downwardly from the longitudinal edges of the board section and the extremities 25 of such end portions are perforated for the passage of adjacent rivets 26 of the rivets 15 for securing the seam cap to the upturned edges 13 of the roof plates.

By this arrangement I am able to utilize, in rigidly connecting the mounting plates to the seam caps the same rivets which are used to rigidly connect the seam caps to the upturned edges 13 thereby dispensing with the necessity of drilling separate holes and using separate rivets. By extending the end portions of the mounting plates outwardly beyond the longitudinal edges of the board section the point of connection between the mounting plate and the seam cap is located substantially far enough outwardly from the longitudinal edges of the board section so that no part of the board interferes with the riveting operation to connect the mounting plates to the seam caps. By extending the end portions of the mounting plates downwardly the intermediate portion 21 of such plates is disposed in a plane free from contact with the rivets of the seam cap adjacent thereto.

These end portions of the mounting plates are offset laterally from the intermediate portion thereof so as to dispose the major portion 28 of the plates in spaced relation with respect to the adjacent sides of the seam cap 14. Such an arrangement compensates for any irregularities in the form of the seam cap which might result by virtue of temperature, faulty installation, or undue strain transmitted to the seam cap while the railway car is in transit or during switching operation.

From the description herein, it will be particularly noted that the running board section and its mounting plates are assembled as a complete unit whereby they may be conveniently installed as a unitary structure at a great saving in labor.

While I have illustrated the mounting plates as being attached to the seam caps, it is understood that my improved running board including its mounting means, may be mounted to the roof of railway cars or other constructions. I therefore do not want to be limited to the precise form of construction of the car roof shown in the drawings.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A running board for a railway car, which car has a roof made up of roof plates arranged in substantially the same plane with adjacent

upturned edges in abutting relation with respect to each other and having a seam cap over each of such abutting edge portions and riveted to such edge portions at spaced intervals, said running board extending along the longitudinal center line of said car comprising transversely extending end plates secured to the running board for installation therewith upon the car roof as a unit of the running board, the opposite outer end portions of said end plates each extending outwardly beyond the longitudinal edges of the running board and each perforated for the passage of a rivet securing the seam cap to the upturned edges of said roof plates, said outer end portions of said end plates each extending downwardly and outwardly of the adjacent longitudinal edge of the running board to a position in facial abutment with an adjacent surface of the seam cap to dispose the intermediate portion of said plates in a plane above any intermediate rivets positioned between said outer end portions of said end plates, said running board having longitudinal parallelly extending spaced apart reinforcing ribs intermediate the longitudinal edges thereof, the ends of said ribs being in abutment with the end plates and welded thereto.

2. A running board for a railway car, which car has a roof made up of roof plates arranged in substantially the same plane with adjacent upturned edges in abutting relation with respect to each other and having a seam cap over each of such abutting edge portions and riveted to such edge portions at spaced intervals, said running board extending along the longitudinal center line of said car comprising transversely extending end plates secured to the running board for installation therewith upon the car roof as a unit of the running board, the opposite outer end portions of said end plates each extending outwardly beyond the longitudinal edges of the running board and each perforated for the passage of a rivet securing the seam cap to the upturned edges of said roof plates, said outer end portions of said end plates each extending downwardly and outwardly of the adjacent longitudinal edge of the running board to a position in facial abutment with an adjacent surface of the seam cap, the said end portions of said end plates being offset laterally with respect to an adjacent side thereof to space the major portion of said end plate from the adjacent side of the seam cap and to dispose said major portion of said plates in a plane above any intermediate rivets positioned between said outer end portions of said end plates, said running board having longitudinal parallelly extending spaced apart reinforcing ribs intermediate the longitudinal edges thereof, the ends of said ribs being in abutment with the end plates and welded thereto.

3. A running board for a railway car which car has a roof made up of roof plates arranged in substantially the same plane with adjacent upturned edges in abutting relation with respect to each other and having a seam cap over each of such abutting edge portions and riveted to such edge portions at spaced intervals, said running board extending along the longitudinal center line of said car comprising transversely extending end plates secured to the running board for installation therewith upon the car roof as a unit of the running board, the opposite outer end portions of said end plates each extending outwardly beyond the longitudinal edges of the running board and each perforated for the passage of a rivet securing the seam cap to the upturned edges

of said roof plates, the said end portions of said end plates being offset laterally with respect to an adjacent side thereof to space the major portion of said end plate from the adjacent side of the seam cap and to dispose said major portion of said plates in a plane above any intermediate rivets positioned between said outer end portions of said end plates, the longitudinal edges of said running board extending downwardly and inwardly to provide a seating flange and said end plates at their opposite end portions being notched to provide a seat for said seating flanges.

4. A running board for a railway car which car has a roof made up of roof plates arranged in substantially the same plane with adjacent upturned edges in abutting relation with respect to each other and having a seam cap over each of such abutting edge portions and riveted to such edge portions at spaced intervals, said running board extending along the longitudinal center line of said car comprising transversely extending end plates secured to the running board for installation therewith upon the car roof as a unit of the running board, the opposite outer end portions of said end plates each extending outwardly beyond the longitudinal edges of the running

board and each perforated for the passage of a rivet securing the seam cap to the upturned edges of said roof plates, said outer end portions of said end plates each extending downwardly and outwardly of the adjacent longitudinal edge of the running board to a position in facial abutment with an adjacent surface of the seam cap, the said end portions of said end plates being offset laterally with respect to an adjacent side thereof to space the major portion of said end plate from the adjacent side of the seam cap and to dispose said major portion of said plates in a plane above any intermediate rivets positioned between said outer end portions of said end plates, the longitudinal edges of said running board extending downwardly and inwardly to provide a seating flange and said end plates as their opposite end portions being notched to provide a seat for said seating flanges.

CHARLES S. JOHNSTON.
